UNITED STATES PATENT OFFICE.

HENRY L. DOHERTY, OF NEW YORK, N. Y.

APPARATUS FOR GENERATING STEAM.

Application filed March 30, 1921. Serial No. 457,159.

This invention relates to apparatus for generating steam and more particularly to steam generating apparatus of the type comprising a boiler and an economizer.

5 An object of the invention is to provide a boiler constructed and arranged to present a large amount of heat transferring surface in proportion to its size. To this end an important feature of the invention consists 10 in a boiler comprising a vertically disposed shell having fire tubes opening through its upper and lower heads and being surrounded by a flue arranged to conduct a heating medium downwardly about the shell 15 of the boiler and into the lower ends of the fire tubes, through which the heating medium flows upwardly in continuous heat transferring relation to the boiler. In the illustrated construction, the flue surrounding the boiler is made spiral, thus causing the heating medium to have a long traverse 20 around the shell of the boiler and to be confined in spaces of limited cross-section so as to cause it to move at a relatively rapid rate. 25 A further object of the invention is to prevent so far as possible the formation in the boiler of deposits or incrustations, such as usually attend the operation of boilers due to the precipitation of solid matter contained in the feed water. In this aspect of 30 the invention another of its important features resides in the provision of means for continuously removing precipitatable material from the boiler before it has been deposited by evaporation. Such means preferably, comprises a siphon having its legs immersed in the water in the boiler and the economizer respectively. Flow of water is induced through the siphon from the boiler 35 to the economizer by reason of the temperature of the water in the boiler being higher than that in the economizer.

The greater portion of the matter ordinarily found in boiler feed water may be 45 divided into two groups; first, matter which is rendered insoluble by heating the water substantially to 270° F. and hence is precipitated, and second, matter which is more soluble in hot water than in cold water and 50 is precipitated only when the solution is concentrated by evaporation of the water. The first group includes the carbonates of calcium and magnesium which are the cause of so-called temporary hardness. When 55 water containing such substances is heated to boiling point, they are rendered insoluble

by the driving off of carbonic acid from the water. Included in the first group also is calcium sulphate which becomes insoluble above 270° F. Substances belonging to 60 the second group which occur most frequently in boiler feed water are sodium sulphate and salt.

A further feature of the invention resides in the provision in a system comprising 65 a boiler and an economizer of means for causing both substances which are insoluble in hot water and those which are of greater solubility in hot water than in cold water to be precipitated in the economizer. 70 The siphon which connects the economizer and the boiler is utilized in carrying out the last-mentioned feature of the invention in connection with means for introducing feed water into the bottom portion of the economizer and for circulating a heating medium 75 downwardly in heat interchanging relation with the water in the economizer. In the use of a steam generating apparatus thus constructed, the water in the lower portion 80 of the economizer is relatively cold, but as it rises in the economizer it is heated by the combined action of the heating medium and the hot water siphoned from the boiler to a point such as to throw down solids in 85 insoluble in hot water. The water which flows from the boiler to the economizer is highly charged with soluble matter by reason of evaporation in the boiler, and a large proportion of the matter held in solution in 90 the boiler water is less soluble in cold water than in hot water. When the water from the boiler is reduced to the low temperature prevailing in the lower portion of the economizer, therefore, solid matter is precipitated 95 from it.

The invention will be herein illustrated and described in connection with a gas producer. It is recognized, however, that the invention is not limited in its application to 100 gas producers and that it may be employed generally for the generation of steam. It is, therefore, intended that the scope of the invention shall not be restricted except as required by the claims.

105 In the drawings which illustrate a preferred embodiment of the invention;

Fig. 1 is a longitudinal vertical sectional view of the boiler and associated parts;

Fig. 2 is a plan view along the line 2—2 110 of Fig. 1; and

Fig. 3 is a vertical section through one of

the tubes for cleaning the boiler flue, taken on the line 3—3 of Fig. 2.

The steam generating apparatus illustrated in the drawings comprises a boiler 10 mounted in a setting 12 of suitable refractory material. In the present embodiment of the invention, a single boiler unit and associated parts, as hereinafter described, are employed, but instead a plurality of such units banked together in some suitable manner may be utilized if preferred. Duplicate parts have not been illustrated since such illustration is deemed unnecessary. The boiler 10 is of the so-called vertical return flue fire-tube type and comprises tubes 14 grouped within a cylindrical shell 16 around a central open-ended tube or pipe 18. The tubes 14 open at their opposite ends through the upper and lower heads 20 and 22 of the shell 16. The pipe 18 serves as a circulation pipe for the water in the boiler. As shown, the pipe 18 extends from a point a few inches below the water level at the top of the boiler to within a few inches of the bottom or lower head 22. The pipe 18 may, if desired, be constructed in sections, or in the form of a roll of fine mesh screen fabric which may be coated with some suitable paint to fill the openings in the fabric and to reduce friction. The present showing with reference to this pipe is virtually diagrammatic, and is to be understood as covering all of the features above specified.

The setting 12 of the boiler 10 is square or 35 rectangular in horizontal section on the outside and circular on the inside, the inner surface being spaced from the shell of the boiler. In the illustrated construction the boiler is employed in connection with a gas producer, and one wall of the setting 12 is 40 equipped with an inlet opening 24 for the hot gases of combustion which issue from the producer. The opening 24 is preferably located a short distance below the water line 45 of the boiler and communicates with a conduit 28 connected to the gas producer. Since the gas producer forms no part of the invention, it has not been illustrated.

The space between the boiler 10 and the 50 cylindrical inner wall of the setting 12 contains a partition wall 23, which extends spirally around the boiler from the inlet 24 leading from the gas producer to a chamber 30 at the bottom of the setting. In consequence, there is produced a spiral flue 32 which conducts the hot gases from the producer around the boiler 10 to the bottom chamber 30. The fire tubes 14 of the boiler are open to the chamber 30 and to a chamber 55 34 formed in the setting 12 at the top of the boiler. With this construction, the gases from the producer are circulated downwardly in heat transferring relation to the boiler from a point near its top to its bottom, and 60 are then caused to flow upwardly through

the fire tubes 14. The boiler is thus caused to present a very large heat transferring surface in proportion to its size. The transfer of heat to the boiler is further enhanced by the provision of the spiral flue 32 which causes the gases to have a long traverse around the boiler and confines them in a space of relatively small transverse area thereby increasing the speed of their flow.

The upper chamber 34 communicates with 75 a conduit 36 surrounding the steam space or dome of the boiler. In this manner, the flue gases are caused to exert as great a superheating effect as possible on the steam before they pass on to the economizer. The steam issues from the boiler through a pipe 37.

Preferably, and as shown, the edge of the spiral wall 26 is arranged in substantial contact with the shell 16 of the boiler. In order to clean the outer surface of the boiler, it is desirable to provide means which may operate in the spiral flue 32. To this end, a tube 38 (Fig. 3) is provided in each corner of the setting 12, and each of the tubes 38 is formed 90 with ports 40 movable into and out of alignment with ports 42 in the setting 12 upon rotation of the tube. In order that the tubes 38 may be conveniently rotated, they are provided with handles 44. The tubes 38 are open at their tops so as freely to admit an air hose or the like 46. When it is desired to clean any portion of the boiler, one of the tubes 38 may be turned to align its ports 40 with the ports 42 of the setting 12, and the air hose may then be employed to direct a blast of air successively through the ports 40 and 42 from the top to the bottom of the setting.

To prevent the baking of any scale-forming substances which may collect on the bottom of the boiler, the lower head 22 is preferably protected with an under facing 48 of insulating material of some suitable character. The facing 48 tends to stop the agitation of the water in contact with the head 22 with the result that an annular zone of relatively small circulation is formed (see broken lines in Fig. 1), starting from about the innermost set of flues and extending outwardly to the shell 16, the height of the zone increasing until the shell is reached. The bulk of the deposited solids collects in this zone. In order that these solids may be readily discharged from the boiler, the lower head 22 is expanded at its edge, as indicated in Fig. 1, so as to produce an annular passage or pocket 50 communicating with a suitable blow-off pipe 52. An annular ring 54 is fitted within the rim of the lower head 22 above the pocket 50 and extends downwardly toward the body of the head 22 so as partially to separate the pocket 50 from the body portion of the boiler.

The boiler setting 12 is constructed with 130

a rectangular extension 56 through the upper portion of which the conduit 36 passes. Mounted in the extension 56 adjacent to the boiler 10 is an economizer or feed-water pre-heater 58 comprising a cylindrical shell 60, upper and lower heads 62 and 64, and a number of tubes 66 opening through the heads 62 and 64. The shell of the economizer 58 is spaced from the adjacent walls of the 10 setting, and hot gases from the conduit 36 pass downwardly through the tubes 66 and about the outer surface of the economizer.

The feed water for the economizer 58 is supplied thereto near its bottom by a pipe 15 68, and water is delivered from the economizer 58 to the boiler 10 by a pipe 70 which connects the upper end of the economizer with the pipe 18 in the boiler.

As hereinbefore indicated, feed water, 20 such as is usually available for use in boilers, contains various impurities. These impurities may exist either in a finely divided and suspended state or in solution, and since they are rarely such as are carried off by the 25 steam, they must eventually be deposited either in the economizer or the boiler. In the use of the present invention it is intended that all matter which can be thrown down by heating, such, for example, as the 30 carbonates of lime and magnesium shall be precipitated in the economizer before the feed water reaches the boiler. The matter which still remains in solution is carried on by the water to the boiler, and, if not 35 previously removed from it, such matter would be precipitated on the bottom of the boiler as the water was converted into steam.

In accordance with the invention, means 40 is provided for causing the temperature of the water in the economizer to be raised to a point such as to throw down the solids which are insoluble in hot water and for removing precipitable matter from the boiler before it has been deposited in it. The 45 purpose and effect of such means is to reduce greatly the amount of solid matter deposited in the boiler. The illustrated embodiment of such means includes a U-shaped siphon 72, by means of which a continual 50 flow of water from the bottom of the boiler to that of the economizer is caused to take place. The central section of the siphon 72 enters the boiler through the side at a point above the central pipe 18 but below the level 55 of the water so as to avoid the steam space, and the boiler leg 73 of the siphon extends through and beyond the pipe 18. The leg 73 of the siphon is provided with a return bend 74 which opens upwardly inside of or 60 directly beneath the central pipe 18 in which the water flows downwardly, so as to cause the velocity of circulation of the water in the boiler to tend to increase the flow of water through the siphon from the boiler

to the economizer. The other leg 75 of the 65 siphon 72 passes through a manhole or cover 76 on the economizer. In order that the cover 76 and the leg 75 may be removed to allow the economizer to be cleaned, the leg is removably coupled to the central section 70 of the siphon as indicated at 78. The central section of the siphon is preferably enclosed by insulating material 80 in order to prevent the formation of steam in it.

Inasmuch as a large part of the heat of the 75 flue gases is absorbed by the boiler, the water in the economizer is heated by them to a much less degree than that in the boiler. Consequently, by reason of the expansion of water when heated, the water in the boiler leg 73 of the siphon is lighter than that in the economizer leg. It follows, therefore, 80 that flow of water is induced through the siphon 72 from the boiler 10 to the economizer 58. The greater weight of the water in the economizer leg of the siphon as compared with that in the boiler leg is due to the transfer of heat from the water in the siphon to the water in the economizer. Accordingly, 85 the more rapidly heat is transferred from the siphon to the water in the economizer, the more rapid will be the flow of water through the siphon. In order to increase the flow of water, the economizer leg 75 is constructed so as to cause rapid interchange of heat between the water in the siphon and that in the economizer. To this end the pipe leading from the boiler is connected adjacent to the top of the economizer with a header 82 from which depends 90 a number of small tubes 84 which provide a large amount of heat interchanging surface. The combined capacity of the tubes 84 is considerably greater than that of the siphon 72, so that a relatively slow flow through the tubes will suffice to induce a 95 considerable flow through the siphon. Moreover, the slow discharge of water from the lower ends of the tubes 84 prevents disturbance of deposits of solid matter on the bottom of the economizer 58.

In order to precipitate to the greatest possible degree matter such as the carbonates of lime and magnesium which may be rendered insoluble by heating, the water must be raised substantially to the boiling point before it leaves the economizer. When the producer is operated at a low rate, however, the heat of the gases from it may be absorbed by the boiler to an extent such that the gases alone will not heat the water in the economizer to the point required. In such a case, the water conducted from the boiler to the economizer by the siphon 72 will supply sufficient additional heat to effect the desired precipitation.

The manner in which heat is transmitted to the water in the economizer and the man-

ner of introducing water into the economizer are such as to produce a stratification of the water into what may be termed "heat zones". A hot layer of water at the top of the economizer and a cold layer at the bottom are particularly well defined.

When the producer is operated at a high rate, thus causing the heating gases to be supplied to the boiler in larger quantity and at a higher temperature, the water in the boiler is evaporated more rapidly. Increase in the rate of evaporation induces a more rapid circulation of the water, which in turn causes an increased flow of water through the siphon 72. Moreover, when the producer is operated at an increased rate, the heating gases pass to the economizer at a higher temperature. Consequently, when water is supplied more rapidly to the boiler from the economizer to replace that which is evaporated, an increased amount of heat is imparted to the water in the economizer so as to heat the increased amount of water passing through the economizer to the required degree.

The arrangement of the parts is such that the water at the top of the economizer is brought substantially to the temperature at which the water boils under the pressure obtaining in the boiler. The heat transfer required to be effected through the shell and the fire tubes of the boiler is thereby reduced to a minimum, thus enabling steam to be generated in the boiler at a very rapid rate and with high efficiency.

Boilers are generally operated under a predetermined gage pressure, which causes the water to boil at a temperature considerably above 270°. In the ordinary use of the apparatus of this invention, the water in the boiler 10 and economizer 58 is heated above 270° thus causing any calcium sulphate which may be present in the feed water to be precipitated in the economizer. If calcium sulphate does, however, enter the boiler, it eventually separates from the water in the form of a light, flocculent precipitate which is held in suspension by the rapidly circulating water for a considerable time. A considerable part of it is, therefore, carried back to the economizer through the siphon 72.

As previously indicated, the water in the boiler becomes highly charged with matter in solution by reason of evaporation of the water. The continual flow of highly charged water from the boiler through the siphon 72 and its replacement by fresh water from the economizer 58 counteracts the tendency of evaporation to produce saturation and hence reduces the precipitation of solid matter in the boiler. A large portion of the matter contained in the boiler is of less solubility in cold water than in hot water. Con-

sequently, when the water from the boiler is mingled with the cold layer of water in the bottom portion of the economizer, solid matter is precipitated from it.

From the foregoing it will be clear that the arrangement of the parts of the apparatus whereby cold water is supplied to the bottom portion of the economizer and the economizer is heated by a downwardly circulating heating medium in connection with the use of the siphon 72 results in the precipitation in the economizer of the bulk of the matter contained in the water, including both that which is rendered insoluble by heating and that which is more soluble in hot water than in cold water. In the use of the apparatus of this invention, therefore, the economizer alone requires frequent blowing-off or cleaning, since only a small part of the matter contained in the feed water is deposited in the boiler. Not only is it advantageous that only one member of the system requires cleaning instead of both, but solid matter may be removed much more readily from the economizer than from the boiler since the bottom of the economizer is not hot enough to cause the precipitated matter to bake on it or to form in a hard crust.

The lower head of the economizer 58 is preferably insulated in a manner similar to the head 22 of the boiler, and the bottom of the economizer is provided with a circumferential pocket 85 connected with a blow-off pipe 86. The solids precipitated in the economizer may be removed periodically or continuously by blowing off through the pipe 86.

As shown, the economizer 58 is supported on spaced shelves 88 projecting inwardly from the setting. Gases outside of the economizer pass through the spaces between the shelves 88 and, together with the gases from the tubes 66, enter an opening 90 leading to a flue 91 (Fig. 2).

The conduit 36 above the economizer communicates directly with a recuperator 92 provided within the extension 56 of the setting, so that a portion of the gases entering the conduit 36 is caused to pass through the economizer tubes 66, while the remaining portion in an amount determined by a gate 93 in the conduit 36 enters the recuperator where it passes through a nest of thin metal tubes 94 which are set in upper and lower disc heads 96 and 98. The economizer and recuperator thus operate in parallel on the gases which have passed the boiler. The recuperator flues are utilized to heat the air delivered to the producer, the air entering the recuperator through a conduit 100 and circulating between the flues 94. The warm air issues from the top of the recuperator through a conduit 102 and is conducted to the producer, preferably through underground flues. The gases, on passing through

the tubes 94 enter the chamber 104 beneath the recuperator, and then pass through an opening 106 to a flue 108.

Having fully described the invention, 5 what is claimed is:

1. In an apparatus of the class described, an upright fire tube boiler and a furnace therefor, a feed water preheater, an inverted U-shaped conduit having one leg in the pre- 10 heater and the other leg in the boiler, the last-named leg having its lower end turned upwardly, said end being located near the bottom of the boiler and substantially in the axis thereof, an open-ended tube extending 15 upwardly from said upturned end and in vertical alignment therewith the top of the tube terminating short of the water line in the boiler, said boiler and furnace being so constructed and arranged as to produce a down- 20 ward circulation of water within said open-ended tube, and a feed water pipe connecting the preheater with the upper portion of said tube.

2. In an apparatus of the class described, 25 an upright boiler and a furnace therefor, a central upright open tube within the boiler, said furnace and boiler being so constructed and arranged as to produce a downward circulation of water in said open-ended tube, a 30 supply pipe connected to the upper portion of said open tube and an exit pipe having an upwardly directed return bend disposed within the central open pipe.

3. In an apparatus of the class described, 35 a boiler, a furnace for said boiler, a central upright open tube within the boiler, said furnace and boiler being so constructed and arranged as to produce a downward circulation of water within said open-ended tube, a 40 economizer, a water supply pipe leading to the lower portion of the said economizer, a feed water pipe leading from the upper portion of the economizer to the upper portion of said tube, and an exit pipe leading 45 from the lower portion of the boiler to the lower portion of the economizer, said exit pipe having an upwardly directed opening near the bottom of the boiler and in alignment with the bore of said central tube.

50 4. In an apparatus of the class described, a boiler, a furnace for said boiler, a central upright open tube within the boiler, said furnace and boiler being so constructed and arranged as to produce a downward circulation 55 of water within said open-ended tube, an economizer, a water supply pipe leading to the lower portion of the economizer, a second water supply pipe leading from the upper portion of the economizer to the upper portion of said tube, a siphon tube leading 60 from the lower portion of the boiler to the lower portion of the economizer, a sediment draw-off pipe connected to the bottom of the said boiler, and a second sediment 65 draw-off pipe connected to the bottom of

the said economizer said siphon including a leg within the tube having its bottom terminal upwardly directed and arranged in the path of the water flowing down through said open-ended tube.

5. The combination with a boiler, an economizer, and a furnace for said boiler, said boiler and said economizer each comprising upper and lower heads connected by a set of substantially vertical fire tubes, of 75 an open-ended upright tube arranged centrally in the boiler, said boiler and furnace being so constructed and arranged as to produce a downward circulation of water in said open-ended tube, said tube having its 80 upper end disposed below the water line and its lower end spaced from the lower head, a siphon having one leg extending through said tube, and its other leg disposed within the economizer, the last-named leg being 85 composed of small pipes extending at their free end into the bottom portion of the economizer and the siphon leg within the tube having its bottom terminal upwardly 90 directed and arranged in the path of the water flowing downward through said open-ended tube.

6. The combination, with a boiler, an economizer, and a furnace for said boiler, said boiler and said economizer each comprising upper and lower heads connected by a set of substantially vertical fire tubes, of 95 an open-ended tube arranged centrally in the boiler and having its upper end disposed below the water line and its lower end 100 spaced from the lower head, said boiler and furnace being so constructed and arranged as to produce a down-flow of water in said open-ended tube, a pipe arranged below the water levels in the boiler and economizer and serving to connect the economizer with said tube, blow-off pipes connected to the said boiler and economizer, and an inverted U-shaped conduit having one leg within the 105 boiler and having its other leg within the 110 economizer and extending at its free end into the bottom portion of the economizer the leg within the boiler having its lower open terminal turned upwardly adjacent the bottom opening in said open-ended tube and arranged in the path of the water flowing 115 downwardly therethrough.

7. The combination with a boiler and an economizer of means for supplying feed water to the boiler from the economizer and an inverted U-shaped conduit arranged to conduct water from the boiler to the economizer, said conduit having one of its legs in the boiler and its other leg in the economizer, the leg in the economizer comprising a plurality of pipes of larger combined heat interchanging surface and capacity than the main body of the conduit in order to induce a relatively large flow of water 120 through it and to reduce the velocity of flow 125 130

of the water in the economizer leg of the conduit, the lower terminal of the leg within the boiler having an upturned end located substantially in the axis of the boiler, 5 and means for directing a stream of fluid into said upturned end.

8. The combination with a boiler, an economizer, and a furnace for said boiler, said boiler and said economizer each comprising upper and lower heads connected by a set of substantially vertical fire-tubes, 10 of an upright open-ended tube arranged centrally in the boiler and having its upper end disposed below the water line and its lower 15 end spaced from the lower head, said boiler

and furnace being so constructed and arranged as to cause a downward flow of water in said open-ended tube and a siphon having one leg extending through said tube and terminating at its free end in an upwardly directed return bend disposed within 20 said tube and having its other leg disposed within the economizer, the last-named leg being composed of small pipes extending at their free ends into the bottom portion 25 of the economizer, and a feed water pipe leading from the economizer to the upper end of said tube.

In testimony whereof I affix my signature
HENRY L. DOHERTY.
